UNITED STATES PATENT OFFICE.

JAMES M. DODGE, OF PHILADELPHIA, PENNSYLVANIA, ASSIGNOR TO THE STAIR LIFT COMPANY, OF PHILADELPHIA, PENNSYLVANIA, AND CAMDEN, NEW JERSEY, A CORPORATION OF NEW JERSEY.

MOVING PLATFORM OR INCLINED PLANE.

No. 802,847.

Specification of Letters Patent.

Patented Oct. 24, 1905.

Application filed January 22, 1898. Renewed November 21, 1901. Serial No. 83,186.

To all whom it may concern:

Be it known that I, JAMES M. DODGE, a citizen of the United States, residing in Philadelphia, Pennsylvania, have invented certain

5 Improvements in Moving Platforms or Inclined Planes, of which the following is a specification.

My invention relates to improvements in moving platforms or inclined planes having 10 either a flat surface or steps, the main object of my invention being to so construct such moving platform or inclined plane when the same is composed of sections that it will be safe and convenient, there being no dangerous 15 or otherwise objectionable gaps or spaces between the sections.

A further object of the invention is to drive the sections of the platform more effectively than usual and to distribute the load.

20 These objects I attain in the manner hereinafter set forth, reference being had to the accompanying drawings, in which—

Figure 1 is a longitudinal sectional view of a traveling inclined plane illustrating my invention. Fig. 2 is a plan view of the same, and Fig. 3 is a view showing my invention used in connection with a moving stairway.

In Figs. 1 and 2 of the drawings, which represent an upwardly-moving inclined plane, 25 A represents a lower floor or fixed platform, B an upper floor or platform, and D the traveling inclined plane, made up of a series of sections d, adapted to ways E at each side. These sections are preferably disconnected 30 and are pushed forward by a driving-wheel F at the bottom of the inclined plane, the teeth of said wheel engaging with the inner sides of the sections d. In the structure shown in Fig. 1 I have also located another driving-

35 wheel F' at the point where the sections are deflected upwardly from the platform B to form the abutment G, and in long runs more of these driving-wheels may be used, if necessary. The sections are adapted to suitable 40 guides at the upper end, which connect with the return-guides, and the several driving-wheels are so operated that they will turn in unison, the purpose of the additional driver or drivers being to relieve the primary driver, especially at or near the points where the 45 platform changes direction, so that the apparatus will work evenly and without loss of power.

In some instances there may be an abutment at both ends of the inclined plane, so 55 that the direction of travel of the sections can be reversed.

It will be understood that a series of drivers may be used in connection with a moving stairway and also that in carrying out my 60 invention I may either use separate step-sections pushed or otherwise moved or enchain sections pulled or pushed. In Fig. 3, for instance, I have shown a movable stairway having step-sections which are driven at three 65 points—that is to say, by a wheel F at the lower end of the structure, by a wheel F' just after the sections turn to form the abutment, and by a wheel F² just after said sections commence to rise to form the stairway, these 70 being the points at which the greatest strains are developed.

My invention can be applied to such an apparatus as set forth in the patent granted to G. A. Wheeler, No. 479,864, dated August 2, 75 1892, in which the step-sections are enchain.

I do not in this application claim specifically the form of my invention wherein the driving sprocket wheel or wheels engage enchain sections, for this forms the subject 80 of my divisional application, filed October 11, 1905, Serial No. 282,241.

I claim as my invention—

1. The combination, in a moving stairway or inclined plane, of guides, sections arranged 85 to travel on said guides, the main driving device at one end of the mechanism, an auxiliary driving device between the two ends of the stairway or inclined plane and engaging the moving portion thereof at a point where 90 it changes direction of movement, substantially as described.

2. The combination, in a moving stairway or platform, of moving sections, guides whereby the sections are directed so as to form an 95 abutment, and a driving device engaging the moving portion of the said platform or stairway at a point where the turn is made to form an abutment, substantially as described.

3. The combination, in a moving stairway or platform, of a moving portion, guides therefor, and a driving device engaging said moving portion on the carrying-run and also on the return run, intermediate the ends thereof, substantially as described. 100

4. The combination, in a moving platform 105

or stairway, of a moving portion, guides therefor, a driving device engaging the carrying-run of the said moving portion at a point between the two ends of the structure and at a point where the said carrying-run changes direction of movement, said driving device also engaging the return run of the moving portion, substantially as described.

5. In a device of the class described, the combination with a portion moving throughout its course in a single vertical plane and made up of a series of sections, of fixed guides supporting said movable portion at both sides, and driving mechanism engaging the carrying-run of the said moving portion at a point between the two ends of the course and where it changes direction of movement, said driving mechanism also engaging the return run, substantially as described.

10 6. In a device of the class described, the combination with a moving portion, guides therefor, a sprocket-wheel engaging the said moving portion on its carrying-run at a point between the two ends of the course and where 15 it changes direction of movement, said sprocket-wheel also engaging the said moving portion on its return run, substantially as described.

7. The combination, in a moving platform 20 or stairway, of a moving portion made up of a series of sections, a driving sprocket-wheel at one end of the mechanism, and an auxiliary driving sprocket-wheel engaging the said moving portion between the two ends of the 25 platform or stairway and at or near a point where the moving portion changes direction of movement, substantially as described.

8. The combination, in a moving platform 30 or stairway, of sections, guides therefor, a main driving device at one end of the mechanism, and an auxiliary driving device engaging with the said sections between the two ends of the platform or stairway and at or 35 near a point where the sections change direction of movement, substantially as described.

40 9. The combination, in a moving platform or stairway, of moving sections, guides whereby the sections are directed so as to form an abutment, means for moving the said sections forward and a driving device engaging the sections as they turn to form the abutment, substantially as described.

45 10. The combination, in a moving platform or stairway, of moving sections, guides therefor, and a driving device engaging the sections between the two ends of the platform or stairway and at a point where they change directions of movement, said driving device also engaging the sections on the return run, substantially as described.

11. In a device of the class described, the combination with the series of connected steps, of ways in which said steps travel, and a driving mechanism intermediate the ends thereof engaging with both the ascending and descending parts of said series, substantially as described.

12. In a device of the class described, the combination with the moving sections of guides for said sections stationary relative to the movement thereof supporting said sections at both ends throughout their entire course, and driving mechanism engaging the sections between the two ends of the course and at a point where they change direction of movement, said driving device also engaging the sections on the return run, substantially as described.

13. In a device of the class described, the combination with the sections moving throughout their course in a single vertical plane, of guides for said sections stationary relative to the movement thereof and supporting them at both ends throughout their course, and driving mechanism engaging the sections between the two ends of the course and at a point where they change direction of movement, said driving mechanism also engaging the sections on the return run, substantially as described.

14. In a device of the class described, the combination with the sections moving throughout their course in a single vertical plane, of guides for said sections stationary relative to the movement thereof and supporting them at both ends throughout their entire course, and driving mechanism engaging the section between the two ends of the course and at a point where they change direction of movement, said driving mechanism consisting of sprocket-wheel engaging said steps on both the forward run and return run, substantially as described.

15. The combination, in a moving stairway, of the moving steps, tracks therefor, and a driving mechanism engaging the steps between the two ends of the stairway and at a point where they change direction of movement, said driving device also engaging the steps on the return run, substantially as described.

In testimony whereof I have signed my name to this specification in the presence of two subscribing witnesses.

JAMES M. DODGE.
